UNITED STATES PATENT OFFICE.

BENJAMIN EDWIN MEACHAM, OF LORAIN, OHIO, ASSIGNOR TO AMERICAN STOVE COMPANY, OF ST. LOUIS, MISSOURI, A CORPORATION OF NEW JERSEY.

THERMOSTATIC FUEL CONTROL FOR GAS-HEATED OVENS.

1,334,776.

Specification of Letters Patent.

Patented Mar. 23, 1920.

Application filed July 7, 1919. Serial No. 309,245.

To all whom it may concern:

Be it known that I, BENJAMIN E. MEACHAM, a citizen of the United States, residing at Lorain, in the county of Lorain 5 and State of Ohio, have invented certain new and useful Improvements in Thermostatic Fuel Controls for Gas-Heated Ovens, of which the following is a specification, reference being had therein to the accompanying drawing.

This invention relates to improvements in thermostatic fuel regulating devices for gas ovens, and it pertains to a thermostatic control for the gas fuel, capable of being adjusted to maintain the desired predetermined temperatures within the oven for slow or fast cooking, as the case may be.

The present improvement relates to the type of regulator shown and described in my Patent No. 1,236,335, dated August 7th, 20 1919, and the primary object of my present improvement is to so construct the operating parts that the regulating wheel for the thermostat is located below the top housing 25 which contains the thermostatic mechanism, whereby the construction is adapted to be used with certain types of stoves for which the location of the adjusting wheel at the upper end of the housing, as in said patent, 30 is not well adapted.

In the accompanying drawings—

Figure 1 shows one type of stove with my present improvement applied thereto and with which it is particularly adapted to be 35 used.

Fig. 2 is a front elevation of another type of stove showing my present improvement applied thereto and with which it is particularly adapted to be used.

Fig. 3 is a vertical central sectional view 40 of my present improvement.

Referring now particularly to Fig. 3, which shows my improved thermostatic mechanism, 1 is a housing carrying at its 45 upper end a thermostatic tube 2, projecting within the oven to be heated. The lower end of the housing 1, has a gas-inlet opening 4, preferably controlled by a hand valve 5. A burner 6 is located within the oven 50 and a gas-outlet nipple 7 communicates with the housing 1, and with the burner 6. A gas controlling valve 8 controls the flow of gas through the nipple 7, and this valve is normally forced toward its seat by a suitable 55 spring 9.

Located within the housing 1, is a lever 10, which has its lower end in engagement with the valve 8, and one end of a yoke 11 is pivoted to the upper portion of the lever 10 at the point 12. A short lever 13 is 60 pivoted to the other end of the yoke 11 at the point 14, intermediate the ends of the lever 13. A roller or wheel 15 is carried by the lower end of the lever 13, and is in engagement with the upper end of the 65 lever 10.

The upper end of the lever 13 has a point or knife edge 16, that is in engagement with a member 17, which in turn engages the outer end of a porcelain rod 18 that is located within the thermostatic expansion and contraction tube 2.

The operation of the thermostat is well understood to those skilled in this art and a description thereof is unnecessary.

A rotatable shaft 19 is screw-threaded into the housing 1, at the point 20, the outer end of the rod carries a notched wheel 21, the notches 22 of which are engaged by a suitable spring latch 23, for the purpose of 80 holding the wheel and rod 19 in their adjusted positions. The periphery 24 of the wheel 21 carries numbers indicating certain degrees of heat, and when the numbers are opposite the pointer (not shown) the degree 85 of heat indicated by the number will be maintained within the oven 3. When the wheel 21 is turned, the screw-threaded shaft is turned with it and moves in or out according to the direction in which it is turned. 90 The inner end of the shaft 19, engages a point or knife edge 25, extending outward from the yoke between its ends. The lower extended end 26 of the yoke 11 rests upon an adjustable screw-threaded plug 27, the 95 function and purpose of which will be presently explained.

As before stated, the spring 9 is normally pushing the valve 8 to its closed position, carrying with it the lower end of the lever 10, which moves the upper end of the lever outward in engagement with the lower end of the lever 13, throwing its upper end inward against the member 17, and normally holding the latter against the end of the porcelain rod 18.

When the oven and thermostat are cold, the thermostatic tube 2 is contracted pushing the porcelain rod 18 toward the housing 1, and causing the inner end of the member 17 110

to force the valve 8 open against the tension of the spring 9, due to the intervening lever construction that has already been explained. When the thermostatic tube 2 expands, the parts move in opposite direction, permitting the spring 9 to move the valve 8 toward its closed position.

The object of the screw-threaded plug 27 is to enable the manufacturer to initially adjust the device to the proper starting position which adjustment is not afterward disturbed.

The parts having thus been initially adjusted by the manufacturer, it is ready for operation. Normally the valve 8 is open and the heating is started by admitting gas to the housing 1, by opening the hand-valve 5 and lighting the burner 6, and the operator turns the wheel 21, either before or immediately after lighting the burner 6, with the indicated heat degree at the spring latch 23. The adjustment of the parts will then be such that the gas-valve 8 will be operated to open or closed position to maintain the desired degree of heat in the oven 3.

By means of the yoke 11 and the compound leverage which has been described, I am enabled to locate the adjusting wheel 21 considerably below the top of the housing 1, whereby when the device is applied to the type of stove shown in Fig. 1, the adjusting wheel 21 is considerably below the top 28 of the oven 3'. Likewise when the device is applied to the type of stove shown in Fig. 2, the wheel 21 is below the top of the oven 3² and sufficiently below the upper oven 3³ to be out of the way and readily accessible for operation.

This location is advantageous because it places the regulating wheel in a position convenient to be operated and it is below the top of the oven and out of the way in crating for transportation.

From the foregoing it will be understood, of course, that the housing 1 is a gas-containing housing when the device is in operation.

Having thus described my invention, what I claim and desire to secure by Letters Patent is:

1. A fuel regulator of the character described, comprising a housing having a thermostat projecting from its upper end and a gas outlet at its lower end, a valve controlling the said gas outlet, a lever mechanism operatively connecting the valve and the thermostat, said lever mechanism including

a yoke, said yoke having one adjusting point and that located between its ends, and a hand adjustable shaft engaging said single yoke adjusting point, whereby the yoke is bodily adjustable from said single adjusting point by the hand operated shaft, for the purpose described.

2. A fuel regulator of the character described, comprising a housing having a thermostat projecting from its upper end and a gas-outlet from its lower end, a valve controlling the gas-outlet, a lever mechanism operatively connecting the thermostat and the valve, said lever mechanism including a yoke, and an adjustable shaft engaging the yoke intermediate its ends, a manually operated member connected with the shaft, the lower end of the yoke having an extension, and an adjustable member engaging the extension of the yoke, the parts combined for the purpose described.

3. A fuel regulator of the character described, comprising a housing having a thermostat projecting from its top, and a gas-outlet at its bottom, a valve controlling the said outlet, a lever mechanism operatively connecting the valve and the thermostat, said lever mechanism including a yoke, and an adjustable shaft engaging the yoke between its ends, a manually operated member connected with the shaft, the lower end of the yoke having an extension, a housing carrying a member engaging the extension of the yoke and adjustable from outside of the housing, the parts combined for the purpose described.

4. A fuel regulator of the character described, comprising a housing having a thermostat projecting from its top and a gas-outlet at its bottom, a valve controlling the gas outlet, a lever within the housing having its lower end operatively connected with the valve, a yoke having its lower end pivoted to the lever below the upper end of the lever, a second lever having its lower end engaging the upper end of the first lever and its upper end operatively connected with the thermostat, the upper end of the yoke pivoted to the second lever intermediate the ends of the lever, and an adjustable shaft operative from the outside of the housing and engaging the yoke intermediate its ends, the parts combined and operating, for the purpose described.

In testimony whereof I hereunto affix my signature.

BENJAMIN EDWIN MEACHAM.
